Inventor:

UNITED STATES PATENT OFFICE.

CLARENCE MAHONEY, OF ELWOOD, INDIANA, ASSIGNOR TO G. I. SELLERS & SONS COMPANY, OF ELWOOD, INDIANA, A CORPORATION OF INDIANA.

LATCH FOR DOORS OF KITCHEN-CABINETS, &c.

1,243,325.

Specification of Letters Patent. Patented Oct. 16, 1917.

Application filed December 28, 1916. Serial No. 138,859.

To all whom it may concern:

Be it known that I, CLARENCE MAHONEY, a citizen of the United States, residing at Elwood, in the county of Madison and State 5 of Indiana, have invented a new and useful Latch for Doors of Kitchen-Cabinets, &c., of which the following is a specification.

This invention relates to improvements in latches, and more especially to that class 10 thereof intended for use upon the doors of kitchen-cabinets and the like, wherein cheapness and facility of manufacture, as well as simplicity, durability, and efficiency, is desirable.

15 The objects of the invention are to produce a latch having the advantages mentioned; and the invention consists in features of construction and combinations of parts hereinafter described and particularly 20 pointed out in the claim.

Referring to the drawing:

Figure 1 is an elevation of a fragmentary part of a kitchen-cabinet compartment-door and the adjacent jamb, such being shown in 25 conjunction with a latch typifying my invention;

Fig. 2 is a front elevation of the latch in detail, the latch-member being shown elevated;

30 Fig. 3 is a plan view of the blank from which the housing is made;

Fig. 4 is a transverse vertical sectional view of the improved latch;

Fig. 5 is a plan view of the blank forming 35 the rear wall of the housing.

Fig. 6 is a detail in elevation of a form of catch that may be employed.

Similar numerals of reference indicate 40 similar parts in all the figures of the drawing.

The entire latch, and catch too, if desired, is produced from suitable gage sheet-metal. In accomplishing this, I employ an oblong blank 1^a, notching the four corners to produce opposite foldable longitudinal side-wings 2^a, and correspondingly located foldable end-wings 3^a, the latter having central attaching-ears 4^a. The described blank being folded on the dotted lines shown, produces the front, opposite side, and opposite end-walls of the rectangular housing 1. The lower central portion of the blank, immediately above the lower transverse or end-wing 4^a, is provided with an oblong longitudinally

disposed opening 6^a, and one of the side-wings has its edge notched or recessed, as at 7^a, for the purpose of forming in the folded blank and housing the opening 7.

The rear wall of the housing is produced from an oblong blank 8^a, the same corresponding in proportion and contour to the housing 1, and at its opposite transverse ends provided with attaching-ears 9^a. The attaching-ears 4^a of the blank 1^a, are perforated, as at 5^a, and the attaching-ears 9^a, 65 of the blank 8^a, are perforated, as at 10^a, to correspond therewith. When these two blanks are assembled, these attaching-ears register, as also do the perforations therein, and they may be swaged together, as indicated at 5. Upon a stud 12, (shown in dotted lines Figs. 1 and 3,) is, in the present instance, pivoted one end of a latch-member 11, the outer free and engaging-end of which projects laterally through the opening 7 of the housing and a sufficient distance therebeyond to effect an engagement with the catch-member 21, secured to the jamb 22, forming a part of the frame of the door 23. Other arrangements for connecting the latch-member within the housing will readily suggest themselves.

The lift-member for operating the latch, like the latter, is stamped from a strip of sheet-metal, and comprises an oblong shank 85 14, and an outwardly and downwardly disposed lift-lug or extension 15. This lift-member is mounted for vertical movement between the front and rear walls of the completed housing, the lift-lug of the member extending forwardly through the opening 6^a thereof, and therefore in a position where it may be readily operated by the finger. At its upper end, the lift-member is preferably formed with a rearwardly bent 90 lug 16; for removable engagement with a corresponding opening 13, formed in the latch-member 11.

The lift-member is of approximately the same width as the elongated opening 6^a of 100 the housing, so that the lower bent portion, 15, of said member passing through and beyond said opening, the vertical edges of the latter being parallel, as stated, will act as guides for said lift-member during the 105 movements of the latter. Some character of guide for the lift-member is necessary because of the fact that the lift-member is

loosely suspended from the latch, and while I prefer to form the guides by means of the opposite edges of the opening 6^a, yet other means for guiding said lift-member 5 will readily suggest themselves.

Any preferred construction of catch-member may be employed in connection with the described latch, but I prefer that shown in Fig. 6. In forming this catch-member I 10 employ simply a strip of sheet-metal of suitable length, bending the same transversely at its middle, as at 18, so that the two terminals lie in close relation and the one reinforces the other. At a suitable distance 15 at one side of the bend 18, the terminals are bent acutely, as at 20, thus forming the head 19 of the catch, and in rear of the same the shank. This shank is made of suitable length, and at a point short of its 20 end, the terminals are diverged in opposite directions and at right angles to the shank, and perforated to receive screws, thus forming attaching-ends 17.

The device is formed of sheet-metal, all 25 parts being readily stamped to shape and readily and cheaply assembled and secured together and in position. For the smaller parts, such as the latch-member, lift, and catch-member, small pieces of sheet-metal 30 may be employed. The device, it will be seen, is devoid of springs, and, operating entirely by gravity, cannot become impaired from constant use, and will remain in effi-

cient operative condition for an indefinite time.

Having described my invention, what I claim, is:

The herein-described latch, formed of sheet-metal, and consisting of a rectangular housing having an opening at one side and a rectangular opening in its front wall at the lower end thereof, a latch-bar pivoted at its inner end within the housing and having its free end extending through the opening in the side of the housing and beyond the same and adapted to engage a catch, and an angularly shaped lifting-member, the lower portion of which is forwardly disposed and extends through and beyond the rectangular opening in the front wall of the housing where it is shaped to form a lift, the said lifting-member approximating in width that of the opening through which it passes, whereby the opposite edges of the opening form vertical guides for the reciprocating movements of the member, and means for loosely connecting the upper end of the lifting-member with the latch-bar.

In testimony whereof I have signed my name to this specification in the presence of 60 two subscribing witnesses.

CLARENCE MAHONEY.
